UNITED STATES PATENT OFFICE.

AXEL UNO STURE DANIELSSON, OF STOCKHOLM, SWEDEN, ASSIGNOR TO AKTIEBOLAGET ATLAS DIESEL, OF STOCKHOLM, SWEDEN.

FUEL-DISTRIBUTING DEVICE FOR MULTICYLINDER ENGINES.

Application filed June 22, 1926, Serial No. 117,822, and in Sweden May 20, 1924.

For the distribution of fuel to the working cylinders of multi-cylinder internal combustion engines delivered by a pump common to the said cylinders, a slide-valve has been proposed located in the discharge channel of the pump and placing the said channel in communication alternately with passages leading to the cylinders. The said slide-valve, preferably cylindrical, has two portions of restricted diameter. In one of the terminal positions of the slide-valve one of the said portions is placed in front of the port of the discharge channel of the pump and the port of one of the delivery passages, while the unrestricted portion located between the said restricted portions covers the port of the second delivery passage. In the other terminal position of the slide-valve the second restricted portion of the same uncovers the port of said discharge channel and the port of the said second delivery passage, while the intermediate unrestricted portion covers the port of the discharge channel first mentioned. Owing to the fact that in internal combustion engines especially of the solid injection type, in which liquid fuel is injected into the combustion chamber of the cylinders at a pressure of about 300 atmospheres, a great pressure of about 150 to 200 atmospheres still prevails in the delivery channels after the performance of the injecting operation, the result is that the said intermediate unrestricted portion of the slide-valve is subjected, when covering the ports of the delivery passages respectively to a considerable lateral pressure, which forces the slide-valve against the side of the valve casing, so that the slide-valve runs stiffly and even sticks fast. The object of this invention is to remove the said disadvantage and for that purpose the said intermediate unrestricted portion of the slide-valve and the distance between the ports of the delivery passages are so adapted with relation to one another that the intermediate portion does not cover the said ports in any position of the slide-valve. Owing to this arrangement the slide-valve is wholly balanced in any position, so that it is easily shifted.

In the accompanying drawing Fig. 1 shows in a side view and partially in section as much of an internal combustion engine as is necessary for explaining the invention. Fig. 2 shows in a side view and diagram-

matically a two-cylinder engine provided with a distributing device in accordance with Fig. 1.

The fuel distributing device shown in the drawing is adapted to an engine of the two stroke system and provided with two working cylinders A and B. 1 is the plunger of the fuel pump. Owing to the fact that two ignitions are effected during each revolution of the crank shaft 2 of the engine, the plunger 1 must perform two working strokes during one revolution of the said shaft in order to feed fuel to each cylinder. In the form of execution shown in the drawing this is effected by the plunger 1 being driven by a cam disk 3 having a single projection and provided on an auxiliary shaft 4, which is rotated by the shaft 2 by means of a spur gearing 5 and 6 and at a number of revolutions twice as great as the number of revolutions of the crank shaft 2. Between the cam disk 3 and the plunger 1 a head 8 is located, which is movable in a guide provided in the frame of the pump and carries a roller 7 bearing against the cam disk 3. Plunger 1 is forced against the said head 8 by a spring 9. The spring actuated suction valve 10 of the fuel pump permits fuel to pass from the admission channel 11, and the spring actuated discharge valve 12 of the pump communicates through a channel 13 with a fuel distributor arranged in accordance with this invention and consisting of a cylindrical slide-valve movable in a casing 14 and having three piston shaped portions 15, 16 and 17. From the casing 14 two conduits 18 and 19 extend to the working cylinders respectively of the engine. Said slide-valve is by a link 20 connected with a bell crank lever 22, which is pivoted at 21 and is acted upon by the rod 23 of an eccentric 24 provided on the shaft 2. The central part 16 of the slide-valve co-operates with the discharge channel 13 of the fuel pump in the following manner. As the slide-valve is shifted by the eccentric 24, the part 16, during the one working stroke of the slide, 1, is placed on the one side of the discharging channel 13 as shown in the drawing, so that the latter through the chamber 26 surrounding the restricted portion of the slide-valve located between the plunger parts 16 and 17 is connected with the pipe 19 communicating with one of the working cylinders of

the engine. During the next stroke of the pump piston the said part 16 is moved to the opposite side of the discharge channel 13, so that the latter communicates with the 5 chamber 25 surrounding the restricted portion between the plunger parts 15 and 16 and with the pipe 18 leading to the second working cylinder of the engine. In this manner the part 16 puts the discharge channel 13 into communication with the two working cylinders alternately. The length 10 of the part 16 is so adapted that the part does not cover in any of its terminal positions the ports of the pipes 18 and 19. Consequently, the slide-valve is never subjected 15 to a lateral pressure from the fuel contained in the said pipes. Besides the slide-valve is always subjected to the same fuel pressure in both directions axially. Consequently, the slide-valve is wholly balanced 20 laterally as well as axially, for which reason the shifting of the same requires slight work. The slide-valve ground in its casing has a very long duration and requires slight 25 inspection. The fuel quantity forced into each working cylinder is controlled by the suction valve 10 which simultaneously operates as an overflow valve and to the suction conduit returns fuel superfluous for the 30 working stroke of the pistons respectively. Valve 10 is opened at the proper moment by a slideable rod 27, which by a spring is forced against a head 28, movable in a guide and acted upon by a cam-disk or an eccentric

30 provided on the auxiliary shaft 4 and adjusted by a governor 29, shown diagrammatically in Fig. 1. The fuel pump and the fuel distributor may, evidently, be combined in such manner, that the pump is actuated upon by a cam-disk provided on the 40 crank shaft 2. The location of the pump and the fuel distributor may easily be adapted to different engine types.

In four cylinder engines two fuel distributors for instance of the type shown in 45 the drawing may be provided, which co-operate with a pump common to the same or with two pumps respectively.

I claim:

In a multi-cylinder internal combustion 50 engine, a device for supplying fuel to two delivery passages from a single pump, including a pump provided with a discharge channel, a slide valve located in said discharge channel and having two portions of restricted diameter adapted to place said discharge channel in communication alternately with said delivery passages, the portion of the slide valve located between the restricted portions and the distance between the delivery passages being so adapted with relation to one another as to prevent covering of said delivery passages by said intermediate portion in any position of the valve.

In testimony whereof I have hereunto 55 affixed my signature.

AXEL UNO STURE DANIELSSON.
